CLAIM

The ornamental design for a weight training bench accessory, as shown and described.

DESCRIPTION

FIG. 1 is a top, front perspective view of a weight training bench accessory;

FIG. 2 is front view thereof, the rear view being a mirror image;

FIG. 3 is a right side view thereof, the left side being a mirror image;

FIG. 4 is a top view thereof;

FIG. 5 is a bottom view thereof;

FIG. 6 is a top, front perspective view of the weight training bench accessory of FIG. 1 placed over a weight training bench;

FIG. 7 is a top, front perspective view of another implementation of a weight training bench accessory;

FIG. 8 is front view thereof, the rear view being a mirror image;

FIG. 9 is a right side view thereof, the left side being a mirror image;

FIG. 10 is a top view thereof;

FIG. 11 is a bottom view thereof; and,

FIG. 12 is a top, front perspective view of the weight training bench accessory of FIG. 7 placed over a weight training bench.

The broken line showing of the weight training bench accessory is for the purpose of illustrating portions of the article that forms no part of the claimed design. The broken lines forming a weight bench in FIGS. 6 and 12 are directed to environment and do not form part of the claimed design. The dot-dash boundary line demarcates the boundary of the claimed areas.
